UNITED STATES PATENT OFFICE

2,673,649

STRAINER

John M. Bass, Sr., Amarillo, Tex.

Application August 6, 1951, Serial No. 240,546

3 Claims. (Cl. 210—159)

1

This invention relates to new and useful improvements in straining devices and the primary object of the present invention is to provide a strainer adapted to be supported over a container and having a pair of supports provided with suitable advertising matter.

Another important object of the present invention is to provide a strainer including a ring member, a mesh material extending across the ring member and novel and improved means for retaining the mesh material across the ring member and free of wrinkles.

A further object of the present invention is to provide a strainer of the aforementioned character wherein the mesh material is quickly and readily removable from the ring member for cleaning, repair or replacement.

A still further aim of the present invention is to provide a strainer that is simple and practical in construction, efficient and reliable in use, neat and attractive in appearance, inexpensive to manufacture, and otherwise well adapted for the purposes for which the same is intended.

Other objects and advantages reside in the details of construction and operation as more fully hereinafter described and claimed, reference being had to the accompanying drawings forming parts hereof, wherein like numerals refer to like parts throughout, and in which:

Figure 1 is a perspective view of the present invention supported on a container (shown in dotted lines);

Figure 2 is a vertical sectional view taken substantially on the plane of section line 2—2 of Figure 1 and with dotted lines showing the retainer pivoted away from the ring member; and

Figure 3 is a bottom plan view of Figure 1.

Referring now to the drawings in detail, wherein for the purpose of illustration, there is disclosed a preferred embodiment of the present invention, the numeral 10 represents a ring member having an outwardly rolled upper edge 12.

A pair of supports 14 and 16 are secured to and project radially outwardly from diametrically opposite sides of the ring member. The support 14 includes an arcuate flanged portion 18 that is fixed against the inner periphery of the ring member by rivets or the like and the support 16 includes an arcuate flanged portion 20 that is also secured to the inner periphery of the ring member by rivets or the like.

The supports 14 and 16 are provided with peripheral or marginal channels or ribs 22 and 24 to eliminate sharp edges and to reinforce the

2

supports. The supports are flat and have advertising matter or indicia on their upper faces.

A flexible mesh material 26 extends across the lower edge of the ring member and against the outer periphery of the ring member. Tongues 28 struck from the ring member engage the material 26 to hold the same relative to the ring member.

Means is provided for retaining the material 26 relative to the ring member and stretched taut across the ring member to prevent wrinkling of the mesh material. This means comprises a sleeve 30 having a laterally projecting portion 32 that is secured to the undersurface of the support 14 by rivets or the like.

A substantially U-shaped or arcuate wire member 34 is formed with a radially projecting central portion 36 that is rotatably supported in the sleeve 30. The ends of the member 34 are bent to form loops 38 that receive terminal hooks of a coil spring 40. The member 34 will yieldingly embrace the ring member to clamp the material 26 thereagainst and the spring 40 will also yieldingly force the material 26 against the ring member.

The material 26 may be quickly and readily removed from the ring member when the retainer 34, 36, 38, 40 is swung to the position shown by dotted lines in Figure 2 and when the tongues 28 are disengaged from the material, to permit cleaning, repair or replacement of the material 26.

Having described the invention, what is claimed as new is:

1. A strainer comprising a ring member, a pair of elongated supports attached to and projecting radially outwardly from diametrically opposite sides of the ring member whereby the ring member may be supported upon the open upper end of a container, a mesh extending across the ring member, a sleeve extending transversely of and secured to the undersurface of one of said supports, a U-shaped wire member having a central offset rotatably positioned in said sleeve, said wire member adapted to embrace the ring member to hold the mesh material thereagainst, and a coil spring terminally secured to the ends of said wire member.

2. A strainer comprising a ring member, a pair of flat supports projecting radially outwardly from diametrically opposite sides of the ring member and having downwardly turned flanges at their inner ends secured to the inner periphery of the ring member, the portions of said supports disposed outwardly from the ring member including raised peripheral edges terminating

at the flanges, and a foraminous member held across the ring member.

3. The combination of claim 2 and circumferentially spaced tongues struck outwardly from the ring member and engaging the foraminous member.

JOHN M. BASS, Sr.
